DESIGN FOR A LADY'S VANITY BOX

George Rosenberg, New Rochelle, N. Y.

Application January 24, 1935, Serial No. 55,039

Term of patent 7 years

To all whom it may concern:

Be it known that I, George Rosenberg, a citizen of the United States, and a resident of the city of New Rochelle, county of Westchester, and State of New York, have invented a new, original, and ornamental Design for Lady's Vanity Box, of which the following is a specification, reference being had to the accompanying drawing, forming a part thereof, wherein:

Fig. 1 is a perspective view of a lady's vanity box embodying the design;

Fig. 2 is a plan view of the same; and
Fig. 3 is an end view of the same.

The dominant features of the design reside in the structure as shown in full lines.

I claim:

The ornamental design for a lady's vanity box, substantially as shown and described.

GEORGE ROSENBERG.
